UNITED STATES PATENT OFFICE

2,518,944

ELECTRIC DISCHARGE DEVICE SEAL

William Joseph Scott, Rugby, England, assignor
to General Electric Company, a corporation of
New York

Application February 2, 1949, Serial No. 74,146
In Great Britain February 13, 1948

5 Claims. (Cl. 250—27.5)

1

This invention relates to electric discharge devices having an envelope of quartz or like vitreous material possessing a high refractive index, the envelope containing a discharge-supporting atmosphere which, during operation, is ionized and emits ultraviolet rays.

In order to achieve and maintain gas tightness of the envelope of such devices the seal(s) between the leading-in conductor(s) to the electrode(s) and the wall of the envelope have to be carefully designed and constructed. The usual form of seal involves the use of a thin foil of molybdenum which, during the manufacture of the envelope, is embedded in a relatively thick rod-shaped stem of the vitreous material of which the envelope is composed, and which is joined to the wall of the envelope. It has been found that the electrical continuity and/or gas-tightness of such seals may deteriorate during the working life of the device, as a result of the action upon the sealed-in conductors of radiation transmitted from the interior of the envelope and along the stem containing the conductor seal, owing to the high refractive index of the vitreous material causing total internal reflection within the stem. This transmission may result in the sealed-in conductor becoming unduly hot, and where it emerges into the air from the vitreous material and joins the usual terminal cap or base at the remote end of the stem oxidation may arise with accompanying deterioration of the conductor.

The principal object of the present invention is to provide means for averting the deterioration of the seal from this cause, and to this end the invention consists in constituting at least a portion of the vitreous material containing the sealed-in conductor of the device of a material which substantially reduces the transmission of radiation along the seal while not affecting the gastightness of it.

This material may be silica, which, by the inclusion of a multiplicity of air bubbles therein, has been rendered opaque to such rays as ultraviolet and infrared and translucent to visible rays. A suitable material of this character is that known as "Vitrosil." A collar or disc of this material is accordingly arranged to constitute an integral part of the stem tube which contains the sealed-in conductor.

In the accompanying drawing, species of the invention are shown in which Fig. 1 is an elevational, partly sectional view of a high pressure mercury vapor discharge lamp embodying the invention and Fig. 2 is a similar view of an elec-

2

trically conducting stem embodying the invention and useful for the lamp shown in Fig. 1.

Referring to Fig. 1 of the drawing, the lamp comprises a spherical envelope 1 of transparent quartz having two stems 2 and 3 protruding therefrom. The electrodes 4 and 5 in the envelope 1 are supported by bent metal rods 6 and 7 emerging from the stems 2 and 3, respectively. The larger electrode 4 is the anode and the smaller electrode 5, which is constituted by the inner end of rod 1, is the cathode of the lamp. The rods 6 and 7 and anode 4 are of tungsten. The envelope 1 contains a starting gas, such as argon, at a few mm. pressure and a quantity of mercury, indicated by the droplet 8, the vapor of which is luminosity producing during operation of the lamp. Lamps of this type are well known and are operated with a power input such that the mercury vapor pressure is of the order of many atmospheres.

The stems 2 and 3 are of similar structure and stem 2 is shown partly in section in Fig. 1 of the drawing to illustrate the structure of the stems. As shown, the stem 2 comprises a tube 9, also of transparent quartz, in which is embedded an electrical conductor including the tungsten rod 6 supporting the electrode 4 and a plurality of molybdenum foil strips 10 which are electrically connected to the inner end of rod 6 by tungsten wires 11 welded to the inner ends of strips 10 and to the end of rod 6. Similar wires 12 are welded to the opposite ends of the strips 10 and extend beyond the end of the stem tube 9 for connection to a base (not shown). The portion of rod 6 in tube 9 is wrapped with molybdenum foil 13 to prevent quartz adhering thereto during fabrication of the stem. The joint between rod 6 and tube 9 is thus a mechanical one. The hermetic joint between the quartz tube 9 and the conductor is at the strips 10 onto which the hot quartz is collapsed during fabrication of the stem to make a gas-tight joint. The stems 2 and 3 usually comprise four or more strips 10 and are capable of carrying a heavy current to the electrodes 4 and 5.

Such stems are known and further description thereof and their method of manufacture are unnecessary for a complete understanding of my invention by those skilled in the art.

50 A disadvantage of stems of this type, as well as with other types of stems, including that shown in Fig. 2 and described below, is in the tendency of the exposed parts of the conductor, that is the tungsten wires 12 and the ends of strips 10 joined thereto, to oxidize at the elevated

temperatures to which they are subjected during operation of the lamp. The oxide coating creeps into the hermetic joints between the strips 10 and the quartz and the joints become gas pervious. Of course, the stems 2 and 3 can be made long enough so that the exposed portions of the conductor are below the oxidizing temperature thereof during operation of the lamp but this expedient increases the cost of the lamp by requiring more material and complicates its shipping and mounting due to its larger size. In accordance with my invention, ultraviolet and infrared rays generated in envelope 1 and travelling within the quartz tube 9 during operation of the lamp are absorbed by an integral collar 14 of quartz containing air bubbles. The stems thus may be made considerably shorter without strips 10 becoming oxidized to the extent that the joints thereof with the quartz become gas pervious for a long useful operating life of the lamp.

The collar 14 is made integral with the stem by heating an annular portion of the quartz tube with a gas flame to vaporize away the quartz of this tube portion. The heating is continued until an annular groove is formed in the tube 9. A rod of quartz containing air bubbles is then heated to its softening temperature and wrapped around the quartz tube 9 to fill up the groove and form an integral part of the stem.

The stem shown in Fig. 2 of the drawing is useful for the lamp shown in Fig. 1 and comprises a metal conductor including a tungsten rod 15 wrapped with molybdenum foil 16 and a molybdenum disc 17 hermetically united around the rod 15 by a brazed hermetic joint 18. The disc 17 tapers to a feathered sealing edge portion which is hermetically embedded in the transparent quartz stem tube 19. A disc or short tube 20 of quartz containing air bubbles is incorporated in the stem tube 19 and the stem is mounted on a lamp envelope with the disc 17 more remote from the envelope than the quartz disc 20. The quartz disc 20, like the collar 14 of Fig. 1, absorbs infrared and ultraviolet radiations generated within the quartz envelope of a lamp and traveling in the stem tube 19. This reduces the temperature of the disc 17 and the tendency of the surface of the disc 17 facing away from the quartz disc 20 and exposed to the outside atmosphere to oxidize. The joint between the thin molybdenum disc 17 and the quartz tube 19 thus remains gas-tight for a long useful life of the lamp.

The quartz disc 20 may be joined to the transparent quartz parts of the tube 19 by butting the ends of transparent quartz tubes against the ends of the translucent quartz disc 20 and heating the joints with a gas flame to the softening temperature of quartz to hermetically fuse the quartz members together. The conductor is then mounted in and joined to the quartz part of the stem by heating the quartz to its softening temperature and collapsing it onto the conductor with which it makes a mechanical joint except at the feathered sealing edge of disc 17 where the joint is hermetic. Stems of this type are disclosed in co-pending application Serial No. 46,916, filed August 30, 1948 and assigned to the assignee of the present application.

What I claim as new and desire to secure by Letters Patent of the United States is:

1. An electric discharge device designed for operation at elevated temperatures and comprising an envelope of material having a high refractive index, an ionizable gaseous atmosphere in said envelope capable of emitting electro-magnetic ra-

diation when excited by an electric discharge and a stem protruding from said envelope comprising a conductor which oxidizes at elevated temperatures and a tube of the envelope material hermetically united around said conductor with a portion of the conductor exposed to the outside atmosphere, an annular portion of said tube between said envelope and the portion thereof hermetically united with said conductor containing air bubbles to minimize the oxidation of the exposed portion of said conductor.

2. An electric discharge device designed for operation at elevated temperatures and comprising a quartz envelope, an ionizable gaseous atmosphere in said envelope capable of emitting electro-magnetic radiations when excited by an electric discharge and a stem protruding from said envelope comprising a conductor which oxidizes at elevated temperatures and a quartz tube hermetically united around said conductor with a portion of the conductor exposed to the outside atmosphere, an annular portion of said tube between said envelope and the portion thereof hermetically united with said conductor including quartz containing air bubbles to substantially reduce the transmission of radiation along the stem and thereby minimize the oxidation of the exposed portion of said conductor.

3. An electric discharge device designed for operation at elevated temperatures and comprising a quartz envelope, an ionizable gaseous atmosphere in said envelope capable of emitting electro-magnetic radiations when excited by an electric discharge and a stem protruding from said envelope comprising a conductor which oxidizes at elevated temperatures and a quartz tube hermetically united around said conductor with a portion of the conductor exposed to the outside atmosphere, a collar of quartz containing air bubbles recessed into the wall of said tube between said envelope and the portion thereof hermetically united with said conductor to substantially reduce the transmission of radiation along the stem and thereby minimize the oxidation of the exposed portion of said conductor.

4. An electric discharge device designed for operation at elevated temperatures and comprising a quartz envelope, an ionizable gaseous atmosphere in said envelope capable of emitting electro-magnetic radiations when excited by an electric discharge and a stem protruding from said envelope comprising a conductor which oxidizes at elevated temperatures and a quartz tube hermetically united around said conductor with a portion of the conductor exposed to the outside atmosphere, an annular section of said tube wall between said envelope and the portion thereof hermetically united with said conductor being of quartz containing air bubbles to substantially reduce the transmission of radiation along the stem and thereby minimize the oxidation of the exposed portion of said conductor.

5. An electrically conducting stem for a high temperature device, comprising an electrical conductor which oxidizes at elevated temperatures and a silica tube hermetically united around a portion of said conductor with an end portion of the conductor exposed at the outer end of the tube, an annular portion of said silica tube containing air bubbles to substantially reduce the transmission of radiation along the stem and thereby minimize the oxidation of the exposed portion of said conductor.

WILLIAM JOSEPH SCOTT.
